UNITED STATES PATENT OFFICE.

WILLIAM KEENAN, OF BROOKLYN, NEW YORK, ASSIGNOR TO BERNARD F. PIEL, OF SAME PLACE.

FELTING-MACHINE.

SPECIFICATION forming part of Letters Patent No. 279,393, dated June 12, 1883.

Application filed April 16, 1883. (No model.)

To all whom it may concern:

Be it known that I, WILLIAM KEENAN, of Brooklyn, in the county of Kings and State of New York, have invented certain new and useful Improvements in Felting-Machines, of which the following is a specification.

My invention relates to felting-machines in which the hats or other articles are felted by passing them between a bed and an apron which have a reciprocating motion, and in which the hats or other articles are carried slowly from the entrance to the exit end of the machine by a continuous movement of the apron in one direction.

My improvements consist, essentially, in a novel construction, form, and arrangement of and means for operating the bed and apron, whereby is produced a machine in which the hats or other articles while being felted are alternately dipped in water and removed therefrom while the felting operation continues; and it further consists in certain details of construction hereinafter described and claimed, and illustrated in the accompanying drawings.

Figure 1 represents a longitudinal vertical section of my improved felting-machine. Fig. 2 represents a transverse vertical section, and Fig. 3 represents a plan thereof. Fig. 4 is a side view of a portion of the machine, which will be hereinafter explained.

Similar letters of reference designate corresponding parts in all the figures.

A is a water box or tank. B is a horizontal shaft extending across and above said box or receptacle. This shaft B supports and operates the felting mechanism, and is mounted in suitable fixed bearings in uprights C C, which are affixed to the sides of the tank A in any appropriate manner.

D D are two similar side frames in the form of sectors suspended at their centers on the shaft B, so that they will be just within the inner walls of the tank A. The radii of said sectors should be of sufficient length to allow them to extend almost to the bottom of the tank A. The frames D D are held together by transverse braces e e, thus forming a skeleton framing.

F is the felting-bed, which is made of inverted-arc form, its concave inner or upper surface being corrugated or ridged. This bed

F is supported upon small spiral springs g g, held in place by the vertical rods h h, which are themselves supported upon small right-angled supports i i, secured to the sector-frames D D. This arrangement gives the bed F a vertically-yielding and elastic support. The frames D D have each in its upper part a vertical oblong slot, k.

l l are journal-boxes, which are fitted to the shaft B, and also to the slots k. Into the upper parts of the said frames D, above the slots k, are fitted screws m, which bear upon the boxes l and support the frames D and the felting-bed F thereon, and which serve to adjust the said frames higher or lower and so adjust the distance between the said bed and the felting or rubbing devices above it.

N is a loose sleeve or hollow shaft, which is fitted to the shaft B, and has secured to it the skeleton framing, composed of the sector-shaped side frames, O, and the transverse brace-rods e e. The radius of these side frames is much smaller than the radius of the frames D, so as to allow the frames O to hang within said frame D and above the bed F.

P P P are rollers, which are loosely journaled in the frames O, and around these rollers extends an endless apron, Q, which presents a lower contour of inverted-arc form, so concentric with the bed F.

At one end of the machine, and at or near the bottom of the tank A, are secured horizontal supports R R, which furnish bearings for the rotary driving-shaft T of the machine, on which are four eccentrics, S S S' S'. The two eccentrics S S are set in the opposite direction to those S' S'. The ends of the sector-frames D D and O O which are nearest to the eccentrics are extended so as to form arms U U and U' U', the arms U U of the frames D D being connected to the eccentrics S S by the eccentric-rods V V, and the arms U' U' of the frames O O being connected to the eccentrics S' S' by the eccentric-rods V' V'. The eccentrics give an oscillating motion to the bed F and the series of rollers P and apron Q, and as the said eccentrics are set in opposite directions while the bed F is moving in one direction the rollers P and apron Q will move in the opposite direction.

On one end of the shaft T is keyed the driv-

ing-wheel W, and upon the other end is keyed a pulley, X. Upon the end of the shaft B, and upon the same side of the machine as the pulley X, is keyed another pulley, Y, and these two pulleys X and Y are connected by an endless belt, Z. Upon the shaft B, between the frames D and O, is keyed another pulley, y, which is connected by a belt, z, with still another pulley, z', keyed to the journal of one of the end rollers, P, outside of the frame O. By means of the driving-shaft T and the pulleys and belts above named a continuous motion is imparted to the apron Q. By the oscillating movements of the bed F and apron Q the hats or other articles which are placed upon the bed F at one end of the machine will be rubbed and felted, while by the continuous movement of the apron Q they will be carried from the end of the bed where they are introduced to the other end and thence delivered. The oscillating movement of the bed and its inverted-arc form also cause the hats or other articles to be alternately dipped in and taken out of the water in the box or tank A, which is advantageous to the felting operation.

What I claim as new, and desire to secure by Letters Patent, is—

1. The combination, in a felting-machine, of a bed and an endless apron the adjacent portions of which are of arc or curved form, and frames for supporting or carrying said bed and apron suspended from and capable of oscillating upon or about a common shaft, substantially as herein specified.

2. The combination of the two oscillating frames, one carrying a felting-bed and the other an endless apron and rollers, and both suspended from the same shaft or axle, a box or trough for containing water, in which the said bed and apron may work, and means for imparting to the said frames oscillating movements in opposite directions, the one to the other, substantially as herein described.

3. The combination, with the oscillating frame which supports the apron and its rollers, of a rotary shaft upon which the said frame oscillates, a pulley on the said shaft, a pulley on one of the rollers within the apron, and a belt running on said pulleys for transmitting motion from the said shaft to the said apron, substantially as herein described.

4. The combination, with the shaft upon which the oscillating frame of the felting-bed and the oscillating frame of the felting-apron and rollers are both suspended, of boxes fitted to the said shaft and to slots in one of said frames, and adjusting-screws between the said boxes and the said frame for adjusting the said frame to regulate the space between said apron and bed, substantially as herein described.

WILLIAM KEENAN.
